NONEVAPORATING OIL TANK

Filed July 18, 1924

FIG. 1.

FIG. 2.

FIG. 3.

FIG. 5.

FIG. 4.

Frank A. Iddings
INVENTOR

BY *C. Chapman*
ATTORNEY.

UNITED STATES PATENT OFFICE.

FRANK ALBERT IDDINGS, OF WARREN, OHIO.

NONEVAPORATING OIL TANK.

Application filed July 18, 1924. Serial No. 726,795.

This invention relates to non-evaporating oil tanks. The prime object of this invention is to provide an oil tank with attachments to a floating deck, that will reduce the evaporation of oil to a minimum.

Other objects of the invention consisting of novel features of construction and arrangements of parts will become apparent, by reference to the following specifications which describe the invention in connection with the accompanying drawings:—

Figure 1 is a sectional view, taken near the center of the device, showing a vertical view.

Figure 2 is a detailed sectional view of the floating deck, showing a depending channel edge and supporting base of a U-shaped bucket, together with a cover plate.

Figure 3 is a perspective view of the U-shaped bucket.

Figure 4 is a plan view of an angularly supporting base of the U-shaped buckets with several pieces of the U-shaped buckets and the cover, in place.

Figure 5 is a perspective view of the cover plate for the U-shaped buckets.

By referring to the drawings, it will be seen that numeral 1, indicates the bottom of the tank, numeral 2 indicates the sides of the tank, and 3 indicates the floating deck. This floating deck 3, is provided with a depending channel edge 4.

By referring to Figure 2, it will be seen that I have provided a supporting base 5, which is secured to the floating deck 3, by means of bolts or rivets. This supporting base 5, is provided with an inturned upper end 7, which slidably supports the U-shaped bucket 8. This U-shaped bucket 8, is provided with a tightly fitting pin 9, having an end 10, fitting loosely in a slot 11 formed in the inturned upper end 7 of the supporting base 5. It will be seen that the lower end 12 of the U-shaped bucket 8, is formed so as to be parallel with and to slidably engage the inner surface of sides 2, of the circular tank.

By referring to Figures 2 and 5, it will be seen that I have provided a cover plate 14, for the U-shaped bucket 8. By referring to Figure 5, it will be seen that I have provided an upwardly formed offset on edge 15, of the cover plate 14. In describing the construction of this device where reference has been made to the figure of the drawing, the single number has been used in reference

to the U-shaped bucket 8, and the cover plate 14. As a matter of fact in the complete assembly of the device there is a plurality of U-shaped buckets 8, and cover plates 14.

The U-shaped buckets 8, may have one edge 13, provided with an offset so that an opposite edge 33, of another U-shaped bucket 8, may slide under it, so that when the U-shaped bucket 8 is in position (see Fig. 2) it presents a perfectly flat surface to rest on the inturned upper end 7, of the supporting base 5. By means of the end 10, of the pin 9, which functions in the slot 11, it will be seen that U-shaped buckets 8, and connecting parts are kept, regularly spaced all around the surface of the inturned upper end 7, of the supporting base 5.

It will be noticed by referring to the drawing that the U-shaped buckets 8, are formed so that when they are in place resting on the inturned upper end 7, of the supporting base 5, with pin 9, functioning in slot 11, the end 12, will bear firmly in a vertical position against the inner wall of the sides 2, of the circular tank, thereby sealing the tank against evaporation.

The pin 9, being fastened firmly through the side of the U-shaped bucket 8, and fitting loosely in the slot 11, will allow the U-shaped buckets 8, to slidably move upwardly and inwardly producing an angular movement on the inturned upper end 7 of the supporting base 5, whenever the U-shaped buckets 8 meet an obstruction, such as alapping joint of the tank plates, or a protruding rivet head. After passing the obstruction or obstructions above mentioned the U-shaped buckets 8 automatically by their own gravity slide back into their position again, engaging the inner side of the sides 2, of the circular tank, thereby preventing evaporation.

The drawing will show that in constructing after the U-shaped buckets 8 have been put in place, as above described, the cover plates 14, which have an offset on edge 15, and curved end 16, are securely fastened to an upper end 17, of the U-shaped buckets 8, by means of a bolt 18, and rest slidably on the lower end 37, of the U-shaped buckets 8. When the cover plate 14 is so attached it is so spaced that the curved end 16 engages the side 2 of the circular tank thereby assisting in preventing the evaporation of oil and preventing the admission of rain.

As one edge of the cover plate 14, is pro-

vided with an upwardly formed offset 15, it will be seen that an opposite edge 35 of another cover plate 14 may slide under it, so that when the cover plate 14 is in position 5 it presents a perfectly flat surface to rest on the ends 17 and 37 of the U-shaped buckets 8. It will be obvious that whenever the curved ends 16 of the cover plate 14 pass an obstruction, such as a protruding 10 rivet head, or lapping joint in the sides 2, of the circular tank, it thereby forces the cover plate 14 inwardly. As these cover plates 14 are securely fastened to the upper end 17 of the U-shaped bucket 8 by means 15 of the bolt 18 and rest slidably on the lower end 37 of the U-shaped buckets 8, the upper end 17 of the U-shaped bucket 8 will move inwardly a sufficient distance to allow the curved end 16 of the cover plate 14, to pass 20 the obstruction, while the lower end 37 of the U-shaped bucket 8 may move inwardly a shorter distance, thereby reducing the unsealing of the tank to a minimum. After 25 the curved end 16 of the cover plate 14 has passed the obstruction the U-shaped bucket 8, by its own gravity will return to normal position engaging the sides 2 of the circular tank, and because of the tension against the upper end 17 of the U-shaped bucket 8, 30 the curved end 16 of the cover plate 14 will be forced back into normal position, against the sides 2 of the circular tank.

Two pipe lines 19 and 20 lead into the circular tank. The sections of the pipes 19 and 20 may be joined together in any manner known to the art. One end of the line 19 is attached to the side 2 of the circular tank, and the other end is rigidly attached to the underside of the floating deck 3, to 35 act as a drain for water or other liquids that may accumulate on the top of the floating deck 3. The line 20 is to act as a supply line to the circular tank, and one end is rigidly attached to the sides 2 of the circular tank, while the other end of the line is 40

rigidly supported at any desired distance below the floating deck 3, so that after the tank has secured a few inches of oil, the discharge of the incoming oil will always be beneath the surface of the oil within 50 the tank, thereby preventing any surface agitation which would tend to induce evaporation.

By referring to Figure 1, it will be seen that the floating deck 3 is provided with 55 legs 21, and a man-hole 22; also truss cables 23. To the upper portion 24, of the sides 2, of the circular tank, are secured in any desirable manner, a plurality of centering cables 25, which are in turn attached to a 60 central post 26, over which slides a collar 27, to which is attached the floating deck 3.

Having thus described my invention, What I claim is:—

1. In an oil tank, a floating deck of less 65 diameter than the tank, means slidably interposed between the deck and the side of the tank, a cover plate over the slidable means and a pin firmly attached to the slid- 70 able means and loosely moving in an under support of the slidable means.

2. In an oil tank, a floating deck of less 75 diameter than the diameter of the tank, U-shaped buckets slidably interposed between the edge of the floating deck and the sides 80 of the tank, a cover attached to the U-shaped buckets, pins firmly attached to the under- 85 side of the U-shaped buckets and loosely moving in slots in the angular support of the U-shaped buckets, a plurality of pipe lines having hinged joints one end of each secured to the sides of the tank the other end of one secured to the underside of the floating deck for drainage purposes; and the other end of another line rigidly se- 90 cured to the underside of the floating deck to act as supply pipe to the tank.

In testimony whereof I affix my signature.

FRANK ALBERT IDDINGS.
